MASSAGE DEVICE

Emil Kosa, Sr., Los Angeles, Calif.

Application January 19, 1940, Serial No. 314,607

3 Claims. (Cl. 128—58)

This invention relates to improvements in massage devices.

The general object of the invention is to provide a novel improved massage device wherein the parts are held together without metal parts.

A more specific object of the invention is to provide a novel massage device including a plurality of roller members mounted on flexible members in novel manner and adapted to engage 10 the user's body.

Other objects and the advantages of my invention will be apparent from the following description taken in connection with the accompanying drawing, wherein:

Fig. 1 is a general view of a massage device embodying the features of my invention;

Fig. 2 is a plan view of one of the roller members;

Fig. 3 is a section taken on line 3—3, Fig. 1;

Fig. 4 is a section taken on line 4—4, Fig. 1;

Fig. 5 is a view showing the device in use;

Fig. 6 is a fragmentary view showing a modified form of my massage device;

Fig. 7 is a view of one of the roller members of 25 the modified form of massage device shown in Fig. 6;

Fig. 8 is a further modification of my massage device; and

Fig. 9 is a section taken on line 9—9, Fig. 8.

Referring to the drawing by reference characters I have shown my invention as embodied in a massage device indicated generally at 10. As shown the device 10 includes a plurality of independent roller members 11 secured adjacent 35 one another as by cords 12 and without the use of metal in a manner to be later described. Ball members 13 adapted to be engaged by the hands of the user are secured to the cords 12.

Each of the roller members 11 preferably made 40 of wood or other similar material is a solid of revolution, shown in Figs. 1 and 2 as an approximate ellipsoid. Each roller member 11 includes a pair of spaced circumferential grooves 14 adapted to engage the cords 12.

A pair of the cords 12 engages each of the 45 grooves 14 crossing as at 15 (see Fig. 3) to hold the roller members 11 in relative position yet permitting rotation thereof and permitting flexing 50 of the entire assembly. The two cords comprising each pair are secured to each other beyond the end roller members as by knots 16.

Each of the ball members 13 includes an axial bore 17 to accommodate the cords 12 as shown in 55 Fig. 4. The bore 17 is enlarged as at 18 to ac-

commodate a knot 19. A plug member 20 closes the bore to present a flush appearance.

In use the ball members 13 are grasped by the user (see Fig. 5) and the roller members 11 are applied to the body in a reciprocating manner. 5 It will be seen that any portion of the body may be easily and effectively massaged by means of this device. The absence of metal assures that the user will not be scratched or harmed due to the use of my device.

In Figs. 6 and 7 I have shown a modified form of massage device indicated generally at 30. As shown the device 30 includes a plurality of roller members 31 held adjacent one another, in a manner similar to that previously described, by cords 12'. The device 30 further includes ball members 13' secured to the cords 12' and similar to the ball members 13.

As indicated in Fig. 7 each of the roller members 31 is substantially cylindrical with hemi-spherical ends and includes a pair of spaced grooves 32 engageable with the cords 12'. Each of the roller members 31 further includes a plurality of helical beads 33 and grooves 34 on the 25 surface thereof.

The device 30 is used in a manner similar to that described for the device 10 with the beads 33 and grooves 34 providing additional massage action.

In Figs. 8 and 9 I have indicated a further modification of my massage device indicated generally at 40. As shown the device 40 includes a plurality of roller members 41 held adjacent one another by cords 42. The device 40 further includes ball members 43 secured to the cords 42 and similar to the ball members 13.

Each of the roller members 41 is substantially cylindrical with hemi-spherical ends and includes a number of spaced circumferential grooves 44 each engageable with a pair of the cords 42. As shown in Fig. 9 each member of each pair of cords 42 is secured to the other member of the pair between each of the roller members as by bindings 45 and beyond the end roller members as by 45 knots 46.

The device 40 is used in a manner similar to that described for the device 10.

From the foregoing description it will be apparent that I have invented a novel massage device which includes no metal and is highly efficient for its intended purpose.

Having thus described my invention, I claim:

1. In a massage device, a plurality of rollers each having a plurality of spaced circumferential 55

- grooves therein, and a pair of cords engageable with each of said grooves, the member of each pair of cords crossing one another between the rollers and holding said rollers adjacent one another but permitting rotation thereof.
5. 2. In a massage device, a plurality of rollers each having a pair of spaced circumferential grooves therein, a pair of cords engageable with each of said grooves and holding said rollers adjacent one another but permitting rotation thereof, the members of each pair of cords crossing one another between said rollers and secured to each other beyond the plurality of rollers, and hand engaging members secured to said cords beyond the rollers.
- 10

3. In a massage device, a plurality of rollers, each of said rollers being of substantially smooth contour and substantially ellipsoidal, each of said rollers having a pair of spaced circumferential grooves therein, and a pair of cords engaging each of said grooves and holding said rollers adjacent one another but permitting rotation thereof, the members of each pair of cords crossing one another between said rollers and secured to each other beyond the plurality of rollers, hand engageable ball members secured to said cords beyond said plurality of rollers.
